UNITED STATES PATENT OFFICE.

EUGÈNE SCHNEIDER, OF LE CREUZOT, FRANCE.

GUN-CARRIAGE.

1,098,334.

Specification of Letters Patent.

Patented May 26, 1914.

Application filed February 14, 1913. Serial No. 748,412.

To all whom it may concern:

Be it known that I, EUGÈNE SCHNEIDER, a citizen of the Republic of France, and resident of Le Creuzot, Saône-et-Loire, France, have invented a new and useful Improvement in or Relating to Gun-Carriages, which is fully set forth in the following specification.

This invention relates to gun carriages of the kind set forth in my prior British Patent No. 7265 of 1912. In the specification of this patent and in that of the application for British Patent No. 14663 of 1912 I have described a form of gun carriage one of the essential characteristics of which is the formation of the rear portion of the trail by a frame the sides of which can be separated. These sides are carried by a base which is pivotally connected to the trail body, this connection permitting the gun as a whole to automatically adapt itself to the nature of the ground so that perfect transverse independence is obtained between the anchoring members and the trail body. The present invention has for its object a special constructional form of this type of gun carriage. According to this invention the aforesaid transverse independence is obtained by means of a pivotal connection between the aforesaid base and the axle or a part integral therewith. In other words the base constitutes the under carriage and it is between this base and the axle or a part fixed on the axle that the longitudinal pivot is arranged.

In order that the said invention may be clearly understood and readily carried into effect the same will now be described more fully with reference to the accompanying drawings, in which:—

Figure 1 is a sectional side elevation. Fig. 2 is a sectional plan. Fig. 3 is a transverse section the parts being represented in the traveling position. Fig. 4 is a section taken on the line A—A of Fig. 3. Fig. 5 is a similar section to that of Fig. 3 the axle being represented in a different position relatively to the frame, and Fig. 6 is a section taken on the line B—B in Fig. 5.

In accordance with the present invention the base *b* of the U-shaped frame *b*, *b'*, *b''* is carried directly by the axle *p* by means of a pivotal connection and consequently the

said base as aforesaid forms the gun carriage head or under carriage.

In the example illustrated the pivotal connection is obtained by two trunnions *k* projecting at right angles from the axle. The carriage *b* which forms the base of the U-shaped frame is fitted upon these two trunnions by means of sleeves *k'*. The sides *b''* of the frame are carried by arms or brackets *b*⁵ integral with the carriage; in the example shown the said sides are provided with pivots *b'* engaging in bearings *b*⁷ integral with the said brackets *b*⁵ in a manner similar to that described and illustrated in the specification of my application for British Patent No. 14663 of 1912. Openings *b*⁶ are formed in the carriage *b* to receive the axle *p* and to allow relative movement between the latter and the frame.

The frame may be made rigid with the axle by means of a locking device such as that more particularly illustrated in Figs. 3 to 6. This device comprises two cams or locking lugs 1 pivoted on the axle *p*; each of these cams or locking lugs is adapted to be brought at will into the locking position (Figs. 3 and 4) or moved aside into a position permitting of relative movement between the frame and axle as shown in Figs. 5 and 6. With this object each of the cams or locking lugs is under the control of a worm 2 carried in bosses 3 fixed to the axle 85 and gearing with a worm sector 4 integral with the said cam.

The upper carriage *z* in which the gun cradle is mounted is guided on the part *b* and is connected thereto by a vertical pivot 5.

The elevating and traversing of the gun are effected by means of any appropriate mechanism.

What I claim and desire to secure by Letters Patent of the United States is:—

1. In a gun carriage, the combination of an axle, a member having a pivotal connection with said axle to permit said member to be swung about an axis lying in the direction of travel of the carriage, and means turning around said axle as a center for adjusting said member.

2. In a gun carriage, the combination of an axle, a member having a pivotal connection with said axle to permit said member

to be swung about an axis lying in the direction of travel of the carriage, and locking lugs movable about said axle for adjusting said member.

5. 3. In a gun carriage, the combination of an axle, a member having a pivotal connection with said axle to permit said member to be swung about an axis lying in the direction of travel of said carriage, and means 10 including cams movable about said axle for adjusting said member.

4. In a gun carriage, the combination of an axle, a member having a pivotal connection with said axle to permit said member 15 to be swung about an axis lying in the direction of travel of said carriage, means turning around said axle as a center for adjusting said member, and means associated with the last-named means for retaining said 20 member in adjusted position.

5. In a gun carriage, the combination of an axle, a member having a pivotal connection with said axle, and means movable into engagement with the under side of said 25 member on opposite sides of said pivotal connection for preventing relative movement between said member and axle during travel of the carriage and movable out of engagement with said member to permit the latter 30 to swing about said pivotal connection when the gun is in firing position.

6. In a gun carriage, the combination of an axle, a member having a pivotal connection with said axle to permit said member 35 to be swung about an axis lying in the direction of travel of said carriage, means including cams movable about said axle for adjusting said member, and means associated with the last-named means for retaining 40 said member in adjusted position.

7. In a gun carriage, the combination of an axle, a member having a pivotal connection with said axle to permit said member to be swung about an axis lying in the direction of travel of the carriage, brackets depending from said member and having elongated openings for receiving said axle, and means movable into engagement with the under side of said member on opposite 50 sides of said pivotal connection for preventing relative movement between said member and axle during the travel of the carriage and movable out of engagement with said member to permit the latter to swing about said pivotal connection when the gun is in firing position.

8. In a gun carriage, the combination of an axle, a member having a pivotal connection with said axle to permit said member 60 to be swung about an axis lying in the direction of travel of the carriage, brackets depending from said member and having elongated openings for receiving said axle, and means movable about said axle for adjusting 65 said member.

9. In a gun carriage, the combination of an axle, a member having a pivotal connection with said axle, and means movable into engagement with said member on opposite sides of said pivotal connection for preventing relative movement between said member and axle during travel of the carriage and movable out of engagement with said member to permit the latter to swing about said pivotal connection when the gun is in firing 75 position.

10. In a gun carriage, the combination of an axle, a member having a pivotal connection with said axle to permit said member to be swung about an axis lying in the direction of travel of the carriage, brackets depending from said member and having elongated openings for receiving said axle, and means including cams movable about said 80 axle for adjusting said member.

11. In a gun carriage, the combination of an axle, a member having a pivotal connection with said axle to permit said member to be swung about an axis lying in the direction of travel of the carriage, brackets depending from said member and having elongated openings for receiving said axle to permit of relative movement between said member and axle when said carriage is in firing position, means for adjusting said 95 member, and means associated with the last-named means for retaining said member in adjusted position.

12. In a gun carriage, the combination of an axle, a trail-base having a pivotal connection with said axle, and means movable into engagement with said base to lock it in position parallel with said axle and movable out of engagement with said base to permit freedom of movement thereof about said 105 pivotal connection.

13. In a gun carriage, the combination of an axle, a trail-base having a pivotal connection with said axle to permit said base to be swung about an axis lying in the direction of travel of the carriage, and means movable into engagement with said base to lock it in position parallel with said axle and movable out of engagement with said base to permit freedom of movement there- 110 of about said pivotal connection.

14. In a gun carriage, the combination of an axle, a member having a pivotal connection with said axle to permit said member to be swung about an axis lying in the direction of travel of the carriage, and means movable into engagement with said member to prevent relative movement between said member and axle and movable out of engagement with said member to permit it to 115 swing about said axis.

15. In a gun carriage, the combination of an axle, a pivoted member adapted to be swung about an axis lying in the direction of travel of the carriage, and means turning 120

around said axle as a center for adjusting said member.

16. In a gun carriage, the combination of an axle, a pivoted member adapted to be 5 swung about an axis lying in the direction of travel of the carriage, and means including cams movable about said axle for adjusting said member.

In testimony whereof I have signed this specification in the presence of two subscribing witnesses. 10
